UNITED STATES PATENT OFFICE.

ALFRED G. F. KUROWSKI, OF BROOKLYN, NEW YORK, ASSIGNOR TO UNDERWOOD
TYPEWRITER COMPANY, OF NEW YORK, N. Y., A CORPORATION OF DELAWARE.

TYPEWRITING MACHINE.

Application filed April 9, 1921. Serial No. 459,964.

To all whom it may concern:

Be it known that I, ALFRED G. F. KUROWSKI, a citizen of the United States, residing in Brooklyn Borough, in the county of 5 Kings, city and State of New York, have invented certain new and useful Improvements in Typewriting Machines, of which the following is a specification.

This invention relates to typewriting machines which are used exclusively for stencil-writing, such as set forth in my co-pending application, Serial No. 459,618, filed April 8, 1921.

In said co-pending application is disclosed 15 means for simultaneously line-feeding a stencil at the front of the platen, rotating the platen, and feeding an ink ribbon between the stencil and the platen, for making impressions on the rear of the stencil 20 to render the typed matter visible.

One feature of the present invention comprises improved ribbon-feeding means whereby the life of the ribbon may be prolonged. For this purpose, there are provided 25 two rolls, each having a ratchet-wheel attached thereto, and a double pawl member engages either ratchet-wheel.

Another feature of this invention is the provision of an improved replaceable celluloid surface on the platen. A hard surface 30 of this type aids in producing sharp impressions on the stencil, but tends to become worn more readily than the ordinary rubber platen surface. Provision is therefore 35 made for readily replacing the worn celluloid surface.

The stencils are generally small waxed sheets fixed to a cardboard frame, and contain only a few lines of typing. The present invention provides for line-spacing the 40 stencil-holding frame and the platen for several line-spaces and then returning the frame and platen to the initial position. It will be apparent that substantially the same 45 portion of the platen surface is used each time, and that this portion will wear out while the remainder of the surface is still in good condition.

It is another feature of this invention to 50 provide means whereby the platen may be rotated relatively to the stencil-holder and the platen-shaft to bring a fresh portion of the platen surface into use.

Other features and advantages will hereinafter appear.

In the accompanying drawings,

Figure 1 is a vertical section of an Underwood standard typewriting machine as modified by the invention, which is shown applied thereto, only the necessary co-operating elements of the machine being illustrated.

Figure 2 is a front view partly sectioned, of the machine shown in Figure 1.

Figure 3 is a detail view of the ribbon-rolls and their mounting.

Figure 4 is a view similar to Figure 1, and shows the double pawl member after a stencil has been raised to its uppermost position, the pawl being set for co-operation 70 with the left ribbon-roll.

Figure 5 is a view similar to Figure 4, with parts omitted, and shows the double pawl member after a stencil has reached the highest position, the pawl being set for co-operation with the right ribbon-roll.

Figure 6 is a detail vertical section, showing the method of attaching the celluloid surface to the platen.

A carriage, indicated generally by the 80 numeral 10, travels on the usual front rail (not shown) and a rear rail 11, and comprises a shiftable platen-frame 12 having end walls 13 and 14. The frame 12 is supported in the usual manner by arms 15 pivoted at one end on a tie-rod 16 of the carriage, and supporting the frame at the other end 17. The shift-frame is provided with a roller 18 riding on a rail 19 integral with frame 20, the latter being pivoted on the 90 machine at 21 and rotatable by a shift-lever (not shown). The end walls of the platen-frame 12 are connected by a tie-strap 22, to which are fixed side plates 23 and 24 connected at their lower ends by a tie-rod 25. 95

A shaft 30 is journaled in the end walls 13 and 14, and in the side plates 23 and 24, and has fixed to the ends thereof knobs, or finger-wheels, 31. The shaft may be rotated in a line-feeding direction by the usual line-space mechanism comprising a handle or lever 32 pivotally mounted upon side wall 13 and operating a slide 33 having a pawl (not shown) engaging the ratchet-wheel 34 fixed on the shaft 30. A platen 35 is loosely mounted upon shaft 30 between the side plates 23 and 24, and is made to rotate integrally with the shaft by mechanism to be hereinafter described.

To the underside of the tie-strap 22 are 110

fixed, just outside side plates 23 and 24, depending arms, or brackets, 40, terminating in hubs 41, in which is journaled a shaft 42. Upon the shaft 42 is fixedly mounted the 5 stencil-holding frame comprising side arms 43 extending forwardly toward the front of the platen and provided with slots 39 to clear shaft 30, the engagement of said shaft in said slots serving to guide the stencil-holding frame in its up-and-down movement, to be described hereinafter. The arms 43 broaden out toward the front of the machine and support at their forward ends the stencil-holder 44, which comprises two U-shaped members 45 and 46, spaced apart by a filler member 47, thus forming a recess into which stencil frames may be inserted. The stencil frames employed are usually of cardboard or similar material which can 15 not be bent to a large extent without breaking. Nevertheless, it is desirable to make the stencil conform to the curvature of the platen to some extent, especially at the printing point indicated by the raised type-head 20 36. For this purpose, the stencil-holder 44 is given a radius of curvature much larger than that of the platen and substantially equal to the length of side arms 43.

To line-space the stencil-holder upwardly, 25 pins 54 and 55 project into cam slots 56 in the arms 43, said pins being fixed to arms 52 and 53, respectively, on hubs 50 and 51 fixed to move with shaft 30 when the latter is rotated in line-feeding direction by the 30 line-space handle 32 or by the finger-wheels 31. Preferably, the platen is rotated upwardly simultaneously with the stencil-holding frame by means which connect the loosely-mounted platen to the shaft to move integrally therewith. The connecting means 35 comprises a pin 59 at the end of a leaf-spring 58 carried by an arm 57, which may be fixed on hub 50, said pin projecting into an opening 62 in an arm 60 fixed to the platen. Arm 57, spring 58, arm 60, and the 40 platen therefore rotate as a unit when the shaft is rotated. Since the typing on a stencil generally occupies not more than three or four lines, and since the platen and 45 stencil-holder move upwardly and downwardly together, the same portion of the platen is used repeatedly, and that portion will consequently wear out rapidly and have to be replaced. Means are therefore provided 50 for rotating the platen relatively to the shaft and the stencil-holder to bring a fresh portion of the platen surface into use. For this purpose, pin 59 may be withdrawn from opening 62 and the platen rotated to a 55 new position on shaft 30, pin 59 lodging in another opening 64, which may be formed in an arm 63 similar to arm 60, but extending from the shaft in another direction.

For producing sharp impressions on the 60 stencils, the platen is provided with a cellu-

loid surface consisting of two sections 70, 71 positioned longitudinally of the platen, the adjacent edges of said strips lodging beneath grooves formed at the edges of metal strips 72, 73 fixed to the platen by screws 74. If 70 one of the sections is worn out in use, the platen need only be revolved through half a revolution relatively to the shaft by the means hereinbefore described to bring the 75 fresh section into effective position. The sections are, of course, readily replaceable by merely sliding the old section from the 80 grooves of the metal strips 72, 73.

It is desirable to render the typed matter on a stencil visible, and, for this purpose, an ink ribbon 80 is positioned to operate between the stencil-holder and the platen to print on the back of the stencil. The ribbon is led from one of two rolls 84, 85 mounted between the side plates 23, 24, 85 around the platen to the other of said rolls, being guided by guide rollers 81, 82 and 83. Roll 84 is mounted upon shafts 90 and 91 supported in bearings 92 and 93 fixed to the side plates and roll 85 is similarly mounted on the side plates, being mounted upon shafts 94 and 95 supported in bearings 96 and 97 fixed to said side plates. The ink ribbon is wound at each end upon a ribbon-spool 102, 103, the 90 latter being mounted on the ends of shafts 90 and 91, and 94 and 95, which project therein, and between flanges 98 and 99, and 100 and 101, fixed upon said shafts near the ends thereof. When mounted between 100 the flanges, the spools are held against movement relative to the flanges by a pin 105, fixed to each flange and projecting into a groove 104 formed in each end of the spools. The ribbon-spools may be readily inserted 105 or withdrawn from their mounting, due to the fact that one flange of each roll 84, 85 (here shown as flanges 99 and 101) is movable laterally, the shafts 91 and 95 being drawn outwardly in their bearings 93 and 110 97 by knobs 110, 111, against the action of springs 112 and 113 interposed between the flange and the bearing. Said springs also provide the necessary tension to take up 115 any slack in the ribbon when it is being unwound.

As hereinbefore stated, the ink ribbon is wound upon one of the rolls 84, 85 and unwound from the other. The movement of the ribbon is designed to occur simultaneously with the line-feeding of the stencil, so as to present a fresh surface to each succeeding line typed upon the stencil. The movement of the ribbon is accomplished by fixing a ratchet 116, 117 to each roll 84, 85, adjacent one of the side plates, one of said ratchets being operated by a pawl member 120 pivoted at one end of a lever 121, said lever being connected by a link 123 to an arm 124, which may be fixed to the same hub 125 130

50 as arm 52; so that rotation of the shaft in line-feeding direction will rotate both arms 52 and 124 upwardly to raise the stencil frame and actuate the pawl member to 5 drive one of the ratchets and wind the ink ribbon on the corresponding roll. Upon the return movement of the shaft and its attached arms, the pawl member will not operate the ribbon-rolls, the pawl riding idly 10 over the ratchet. It is apparent that, after a sufficient number of stencils have been typed, the ribbon will be completely wound upon one of the rolls 84, 85 with which the ratchet is in engagement. The ribbon is capable of further use, and, hence, means are 15 provided for moving the pawl member into engagement with the other ratchet, so that further line-feeding of the platen winds the roll which had previously been unwound, 20 and thus avoids the necessity of manually rewinding the ribbon. For this purpose, pawl member 120 is provided with two pawls 130 and 131 for co-operation with ratchets 116 and 117, respectively, the pawl member being 25 swung about its pivot into engagement with one or the other of said ratchets, depending upon which roll it is desired to wind. The pawl member is held in engagement with either ratchet, as desired, by a spring 30 detent in the form of a lever 132 pivoted upon lever 121, and having its upper end pressed by a spring 133 connected to its lower end into either of two notches 134, 135 in the pawl member. When the detent 35 lodges in notch 134, as in the Figure 1 position, the detent presses downwardly upon surface 140 of notch 134 to swing the pawl member in a clockwise direction, and hence into contact with ratchet 116; when the detent lodges in notch 135 it presses forwardly 40 against surface 141 of the notch to swing the pawl member in a counter-clockwise direction, and hence into contact with ratchet 117. The pawl member remains in contact 45 with the respective ratchet for a number of line-spaces equal to the maximum number of lines on the stencil, usually not more than three or four. However, by varying the distance of the pawl-member from sleeve 122, 50 i. e., by bringing it closer to or further from ratchet 116, and by varying the size of the parts co-operating with the pawl-member accordingly, the pawls 130 and 131 can be 55 brought into contact with the respective ratchets for a longer or shorter time to vary the number of line-spaces through which the respective ribbon-rolls are rotated.

The complete operation of the device is as 60 follows: Assume the parts to be in the position shown in Figure 1. Upon actuation of the line-space handle 32 or the finger-wheels 31 in a line-feeding direction, shaft 30 and hence arms 52, 53, 124 and 57 will be 65 rotated. Arms 52 and 53 will raise the stencil-holding frame, due to the pin-and-slot

connection therewith; arm 124 will raise link 123 to rock lever 121 and operate pawl-member 120 downwardly to wind the ink-ribbon on roll 84; and arm 57 will rotate the platen upwardly because of the spring-and-pin connection therewith. When the stencil has been fully typed, the shaft 30 is rotated in the reverse direction to return all of the arms and their co-operating parts to the initial position shown in Figure 1. When the ink-ribbon has been fully wound on roll 84, the pawl-member 120 is swung about its pivot to bring pawl 131 into engagement with ratchet 117. The ribbon will then be wound upon roll 85 when shaft 30 is operated in line-feeding direction. It will be observed that, when the ribbon is being wound upon roll 84, it is traveling past the front of the platen in a direction opposite to that of the stencil-holder. This is not objectionable, however, since the stencil is slightly spaced from the platen, except when the type strikes, which would prevent fouling. In any case, a clear ink impression is not essential, the ink backing being merely for the purpose of rendering the stenciling visible. As already pointed out, and as shown in Figure 4, not more than one-half of the platen is utilized in the typing of stencils, and therefore the platen may be rotated through one-half a revolution to bring a fresh part thereof into effective position. The replacement of the celluloid surface will be clear from the description. When an ink-ribbon has been exhausted, it is wound upon one spool 102 or 103, which spool is released by drawing knob 110 or 111 outwardly, and a new spool or ribbon is inserted. Variations may be resorted to within the scope of the invention, and portions of the improvements may be used without others. Having thus described my invention, I claim:

1. In a typewriting machine, in combination, a platen-frame, a shaft journaled therein, a platen mounted on said shaft, a stencil-holder mounted for movement in front of said platen, means for line-spacing said stencil-holder, a pair of rolls mounted in said platen-frame, a ribbon passing from one of said rolls between said stencil-holder and platen to the other of said rolls, a separate ratchet connected to each roll, a pawl-device settable at will for co-operation with either of said ratchets to wind the ribbon upon the respective roll at line-space intervals when operated, and means for operating said device simultaneously with the line-spacing of the stencil-holder. 110

2. In a typewriting machine, in combination, a platen-frame, a shaft journaled therein, a platen mounted on said shaft, a pair of rolls mounted in said frame, a ribbon passing from one of said rolls around said platen to the other of said rolls, a separate 115

120

125

130

ratchet connected to each roll, a pawl-device settable at will for co-operation with either of said ratchets, to wind the ribbon upon the respective roll at line-space intervals and 5 unwind said ribbon from the other of said rolls when said device is operated, and a connection between said device and said shaft whereby said device is operated when said shaft is rotated in a line-feeding direction.

3. In a typewriting machine, in combination, a platen-frame, a shaft journaled therein, a platen mounted on said shaft, a pair of rolls mounted in said frame, a ribbon passing from one of said rolls around said platen to the other of said rolls, a ratchet fixed to each roll, a double pawl-member having a separate pawl for engagement with each ratchet, said member being settable at will 20 to engage either of said ratchets to wind the ribbon upon the respective roll when said member is operated, and a connection between said shaft and said member whereby said member is operated when said shaft is 25 rotated in a line-feeding direction.

4. In a typewriting machine, in combination, a platen-frame, a shaft journaled therein, a platen mounted on said shaft, a pair of rolls mounted in said frame, a ribbon passing from one of said rolls around said platen to the other of said rolls, a ratchet fixed to each roll, a double pawl-member having a separate pawl for engagement with each ratchet, said member being settable at will 30 to engage either of said ratchets to wind the ribbon upon the respective roll when said member is operated, a detent, a spring pressing said detent against said member for holding said member in engagement with either of said ratchets, and a connection between said shaft and said member whereby said member is operated when said shaft is 35 rotated in a line-feeding direction.

5. In a typewriting machine, in combination, a platen-frame, a shaft journaled therein, a platen mounted on said shaft, a pair of rolls mounted in said frame, a ribbon passing from one of said rolls around said platen to the other of said rolls, a ratchet fixed to 40 each roll, a double pawl-member having a separate pawl for engagement with each ratchet, said member being settable at will to engage either of said ratchets to wind the ribbon upon the respective roll when said member is operated, said member having two 45 notches, a detent, a spring pressing said detent into said notches, the lodging of said detent in one of said notches pressing said member into engagement with one of said ratchets, and the lodging of said detent in 50 the other of said notches pressing said member into engagement with the other of said ratchets, and a connection between said shaft and said member whereby said mem-

ber is operated when said shaft is rotated in 65 a line-feeding direction.

6. In a typewriting machine, in combination, a platen-frame, a shaft journaled therein, a platen mounted on said shaft, a pair of rolls mounted in said frame, a ribbon 70 passing from one of said rolls around said platen to the other of said rolls, a ratchet fixed to each roll, a double pawl-member having a separate pawl for engagement with each ratchet, said member being settable at 75 will to engage either of said ratchets to wind the ribbon upon the respective roll when said member is operated, said member having two notches, a detent, a spring pressing said detent into said notches, the lodging of said 80 detent in one of said notches tending to turn said member clockwise into engagement with one of said ratchets, and the lodging of said detent in the other of said notches tending to turn said member counter-clockwise into 85 engagement with the other of said ratchets, and a connection between said shaft and said member whereby said member is operated when said shaft is rotated in a line-feeding direction.

7. In a typewriting machine, in combination, a platen-frame, a shaft journaled therein, a platen mounted on said shaft, a pair of rolls mounted in said frame, a ribbon passing from one of said rolls around said platen to the other of said rolls, a ratchet fixed to each roll, a lever pivotally mounted on said machine, a double pawl-member pivotally mounted at one end of said lever, said member having a separate pawl for engagement 95 with each ratchet, said member being settable at will to engage either of said ratchets to wind the ribbon upon the respective roll when said member is operated, and a connection between said shaft and the other 100 end of said lever whereby said member is operated when said shaft is rotated in a line-feeding direction.

8. In a typewriting machine, in combination, a platen-frame, a shaft journaled therein, a platen mounted on said shaft, a pair of rolls mounted in said frame, a ribbon passing from one of said rolls around said platen to the other of said rolls, a ratchet fixed to each roll, a lever pivotally mounted on said 110 machine, a double pawl-member pivotally mounted at one end of said lever, said member having a separate pawl for engagement with each ratchet, said member being settable at will to engage either of said ratchets to wind the ribbon upon the respective roll when said member is operated, a second lever pivotally mounted on said first lever, a spring connecting the lower end of said 115 second lever to said first lever and forcing the upper end of said second lever forwardly 120 against said member for holding said member in engagement with either of said ratch-

- ets, and a connection between said shaft and the other end of said first lever whereby said member is operated when said shaft is rotated in a line-feeding direction.
- 5 9. In a typewriting machine, in combination, a platen-frame, a shaft journaled therein, a line-space mechanism for said shaft, a platen loosely mounted on said shaft, and releasable means for rotatively connecting together the shaft and the platen at relatively different rotative positions, said means comprising a member fixed upon the platen, a member fixed upon the shaft in proximity to the member on the platen, one of said 15 members having therein a plurality of angularly-spaced holes, and a pin movably carried by the other of said members to be engaged in one or another of said holes.
- 10 10. In a typewriting machine, in combination, a platen-frame, a shaft journaled therein, a line-space mechanism for said shaft, a platen loosely mounted on said shaft and having an opening in an end thereof, an arm fixed to said shaft, a spring member fixed to 20 said arm, and a pin fixed to said spring member and lodging in said opening to connect said platen to said shaft, so that said platen and shaft rotate as a unit.
- 11 11. In a typewriting machine, in combination, a platen-frame, a shaft journaled therein, a line-space mechanism for said shaft, a platen loosely mounted on said shaft and having a plurality of openings in an end thereof, an arm fixed to said shaft, a spring 25 member fixed to said arm, and a pin fixed to said spring member and lodging in one of said openings to connect said platen to said shaft, so that said platen and shaft rotate as a unit, said pin being withdrawable 30 against the action of said spring member to permit said platen to rotate to a new position relative to the shaft, said pin engaging in another of said openings to fix said platen to said shaft in the new position.
- 45 12. In a typewriting machine, in combination, a platen-frame, a shaft journaled therein, a line-space mechanism for said shaft, a platen loosely mounted on said shaft, releasable means fixed to said shaft and connected to said platen to cause said platen and shaft to rotate as a unit, the same portion of the surface of the platen lengthwise thereof being subjected to repeated use until said portion is worn out, the releasing of said 50 means permitting the rotation of the platen to a new position relative to the shaft to bring a fresh portion of the platen surface into use, means whereby the releasable means may be connected to the platen to hold the latter in the new position, and a hard surface for said platen comprising a plurality of removable sections lengthwise of the platen, the number of sections corresponding to the effective positions of the platen 55 relative to the shaft.
13. In a typewriting machine, in combination, a platen-frame, a shaft journaled therein, a line-space mechanism for said shaft, a platen loosely mounted on said shaft, releasable means fixed to said shaft and connected to said platen to cause said platen and shaft to rotate as a unit, the same portion of the surface of the platen lengthwise thereof being subjected to repeated use until said portion is worn out, the releasing of 60 said means permitting the rotation of the platen to a new position relative to the shaft to bring a fresh portion of the platen surface into use, means whereby the releasable means may be connected to the platen to hold the latter in the new position, a hard surface for said platen comprising a plurality of removable celluloid sections lengthwise of the platen, and means for holding said sections against movement around said platen to permit withdrawal and insertion of said sections lengthwise of the platen, the number of sections corresponding to the effective positions of the platen relative to the shaft.
14. In a typewriting machine, in combination, a platen-frame, a shaft journaled therein, a line-space mechanism for said shaft, a platen loosely mounted on said shaft, and releasable means for rotatively connecting together the shaft and the platen at relatively different rotative positions, said means comprising a member carried by the platen and having therein a plurality of angularly-spaced holes, an arm carried by the shaft in proximity to said member, and a pin movably carried by said arm to be engaged in one or another of said holes.
15. In a typewriting machine, in combination, a platen-frame, a shaft journaled therein, a line-space mechanism for said shaft, a platen loosely mounted on said shaft, a stencil-holder mounted for movement in front of said platen, means for line-spacing said stencil-holder from said shaft, means for line-spacing the platen from said shaft concomitantly with the line-spacing of the stencil-holder, said line-spacing means for the platen including means for adjusting the rotative position of the platen relatively to the stencil-holder, thereby to bring fresh portions of the platen surface into use, and means operated by said shaft and manually settable for feeding a ribbon in one direction or the other at will at line-space intervals between said platen and said stencil-holder concomitantly with the line-spacing of the platen and stencil-holder.
16. In a typewriting machine, in combination, a platen-frame, a shaft journaled therein, a line-space mechanism for said shaft, a platen loosely mounted on said shaft, a stencil-holder mounted for movement in front of said platen, means for line-spacing said stencil-holder from said shaft, means
